REFRIGERATION APPARATUS PARTICULARLY ADAPTED FOR FREEZING FISH

Carl Sundbäck, Weymouth, Mass.

Application July 16, 1935, Serial No. 31,690

6 Claims. (Cl. 62—102)

This invention relates to refrigeration apparatus, and the object of the invention is to provide an improved construction whereby cold air may be circulated in greater quantity and with 5 greater efficiency than has been possible in constructions heretofore known.

The invention is particularly applicable to the construction of apparatus for storing and freezing fish, whereby the same may be kept in marketable condition.

The invention contemplates refrigeration apparatus comprising a compartment or building including a freezing or storage chamber, an air cooling chamber, and an air tunnel, the latter divided into passageways for separation and direction of air passing between the freezing or storage chamber and the air cooling chamber in currents which may be considered as originating in the air cooling chamber and returning thereto 20 after passage through the freezing or storage chamber, a refrigerating unit being located in the air cooling chamber, and a blower or other air current producing device being used to circulate the air through the refrigerating unit, air tunnel 25 and freezing or storage chamber, all as will be explained hereinafter more fully and finally claimed.

In the accompanying drawing illustrating the invention, the figure is a perspective view of refrigeration apparatus embodying the principles of the invention, portions thereof being broken away to illustrate the construction and arrangement of the parts forming essential features of 30 the invention.

The building or compartment of the apparatus comprises a foundation or bed 1, preferably in the form of a concrete slab the upper surface of which is provided with heat and moisture insulating coverings 1', and upon this slab are erected an outer wall 2 and an inner wall 3, these walls 2 and 3 being spaced apart by suitable framing 4 and the space between them being filled with heat insulating material 5 of any suitable character.

The interior of the compartment is divided substantially midway of its height by a horizontal partition or ceiling member 6, which extends from end to end of the compartment between the inner end walls 3, and this ceiling member provides below it a freezing or storage chamber 7, and above it an air cooling chamber 8.

Above the ceiling member 6 and spaced a suitable distance therefrom is a false ceiling, partition or platform 9 upon which is supported a refrigerating unit 10 of any appropriate type,

having an inlet 11 and an outlet 12 for the circulation of refrigerant therethrough.

The space between the ceiling member 6 and platform 9 provides an air tunnel divided by a diagonal partition 13 which forms two separate 5 tapering air passages open at their large ends and closed at their small ends for separating and directing air currents passing between the air cooling chamber and the freezing or storage chamber.

In the interior of the freezing or storage chamber 7 the side walls are provided with vertical studs 14, tapering from top to bottom and serving to support the ceiling member 6 and platform 9, and to the exposed edges of these studs 15 are applied a plurality of spaced slats 15 forming lattice partitions providing between them and the adjacent walls, flues or ducts for the passage of air currents. The ceiling member 6 is cut away above the ends of the studs 14 throughout 20 its portion which is included within the air tunnel to form at its side edges elongated slots through which air may pass to and from the freezing or storage chamber by way of the slatted or lattice partitions thereof and through the separate passages of the air tunnel, as will be more fully pointed out hereinafter.

The air cooling chamber 8 is divided by a transverse partition 17 into two sections, one of which 30 contains the refrigerating unit 10, and may be termed the refrigerating section, and the other of which contains suitable air circulating means such as a blower 18, and may be termed the return section.

The refrigerating section of the air cooling chamber communicates with the open end of one of the passages of the air tunnel, and the return section of the air cooling chamber communicates with the open end of the other passage of 40 the air tunnel. Thus, air forced in the direction of the arrows A and B will pass from the return section of the air cooling chamber through the blower and through the refrigerating unit and thence over the end of the platform 9 and into 45 the open end of one of the passages of the air tunnel, whence it passes downwardly between the studs 14 and into the freezing or storage chamber. Inasmuch as the blower 18 while forcing air through the refrigerating unit and thence into the freezing or storage chamber, as described, at 50 the same time induces a current of air in the return section of the air cooling chamber, the refrigerated air will pass from side to side of the cooling chamber, as indicated by the arrows C, 55 and so upwardly between the studs 14 at the op-

posite side of the freezing or storage chamber, through the other passage of the air tunnel, as indicated by the arrows D, and thence from the return section of the air cooling chamber back 5 to the blower, as indicated by the arrow E.

It will be noted that the shape of the passages of the air tunnel, and of the ducts or flues of the lattice partition structure 14-15 at the sides of the freezing or storage chamber, is such as to produce 10 the least obstruction to the flow of the air currents set up by the blower 18. Thus, the air circulates through the apparatus, and in contact with the goods placed in the freezing or storage chamber, in large quantities and with great 15 facility, with the result that the refrigerating effect produced is most efficient.

Beneath the refrigerating unit 10 is a drip pan 19 to catch the water produced during defrosting, and this pan has a drain 20 extending exteriorly 20 of the apparatus.

As shown, the freezing or storage chamber may be entered by way of one or more doors 21, and the air cooling chamber may be entered by way of one or more balconies 22 and doors 23.

25 The space between the ceiling member 6 and platform 9 occupied by the air tunnel serves to effectively insulate the air cooling chamber 8 from the freezing or storage chamber 1, and thus any heat which may be produced incident to 30 operation of the blower 18 is prevented from adversely affecting the temperature of the freezing or storage chamber.

Various changes and modifications are contemplated within the spirit of the invention and the 35 scope of the following claims.

What I claim is:—

1. In refrigeration apparatus, a compartment, 40 partitions in said compartment defining a storage chamber, an air cooling chamber, and an air tunnel interposed between and separating said chambers, said air tunnel having separate passages for conducting air to and from said storage chamber and air cooling chamber, means furnishing communication between said chambers 45 and tunnel, a refrigerating unit in said air cooling chamber, and means for circulating air through said refrigerating unit, air tunnel and storage chamber.

2. In refrigeration apparatus, a compartment, 50 partitions in said compartment defining a storage chamber, an air cooling chamber, and an air tunnel interposed between said chambers, one of said partitions comprising a ceiling member forming a wall of said tunnel and separating said 55 storage chamber from said air cooling chamber except by way of said air tunnel, said air tunnel providing two separate passages communicating at their ends with said cooling chamber and at 60 their sides with said storage chamber, a refrigerating unit in said air cooling chamber, and means for circulating air through said refrigerating unit and storage chamber by way of the passages of said air tunnel.

3. In refrigeration apparatus, a compartment, 65 partitions in said compartment defining a storage chamber, an air cooling chamber, and an air tunnel, said air tunnel interposed between and separating said chambers and provided with a diagonally arranged partition dividing the tunnel 70 into two separate passages communicating at

their ends with said air cooling chamber and at their sides with said storage chamber, a refrigerating unit in said air cooling chamber, and means for circulating air through said refrigerating unit and storage chamber by way of said air tunnel. 5

4. In refrigeration apparatus, a compartment, 10 partitions in said compartment defining a storage chamber, an air cooling chamber, and an air tunnel interposed between and separating said chambers and having a diagonally arranged partition dividing the tunnel into two separate passages each having an open end and side affording communication with said chambers for separately conducting air to and from said storage chamber and air cooling chamber, a refrigerating 15 unit in said air cooling chamber, and a blower arranged in said air cooling chamber for circulating air through said refrigerating unit, air tunnel and storage chamber.

5. In refrigeration apparatus, a compartment, 20 partitions dividing said compartment into a storage chamber, an air cooling chamber, and an air tunnel interposed between and separating said chambers and having separate passages for conducting air to and from said storage chamber 25 and air cooling chamber, said tunnel serving to insulate said chambers with respect to each other, means adjacent to one wall of said storage chamber for conducting air from one passage of said air tunnel to said storage chamber, means adjacent to the opposite wall of said storage chamber for conducting air from said storage chamber to the other passage of said air tunnel, a partition dividing said air cooling chamber into a refrigerating section and a return section, said refrigerating section communicating with one passage 30 of said air tunnel, and said return section communicating with the other passage of said air tunnel, a refrigerating unit in said refrigerating section, and a blower associated with said last 40 named partition and adapted to circulate air through said refrigerating unit, storage chamber and return section by way of the passages of said air tunnel. 35

6. In refrigeration apparatus, a compartment, 45 partitions dividing said compartment into a storage chamber, an air cooling chamber, and an air tunnel interposed between and separating said chambers and having separate passages for conducting air to and from said storage chamber 50 and air cooling chamber, lattice partition means adjacent to one wall of said storage chamber providing flues for conducting air from one passage of said air tunnel to said storage chamber, similar lattice partition means adjacent to the 55 opposite wall of said storage chamber providing flues for conducting air from said storage chamber to the other passage of said air tunnel, a partition dividing said air cooling chamber into a refrigerating section and a return section, said refrigerating section communicating with one passage of said air tunnel, and said return section communicating with the other passage of said air tunnel, a refrigerating unit in said refrigerating 60 section, and a blower associated with said last 65 named partition and adapted to circulate air through said refrigerating unit, storage chamber and return section by way of the passages of said air tunnel.
